(12) **United States Design Patent**
Tegg et al.

(10) **Patent No.:** US D762,851 S
(45) **Date of Patent:** ** Aug. 2, 2016

(54) **CONTROL HANDLE FOR A MEDICAL DEVICE**

(71) Applicant: **St. Jude Medical, Atrial Fibrillation Division, Inc.**, St. Paul, MN (US)

(72) Inventors: **Troy T. Tegg**, Elk River, MN (US); **Andrew Senn**, Minneapolis, MN (US)

(73) Assignee: **St. Jude Medical, Atrial Fibrillation Division, Inc.**, St. Paul, MN (US)

(**) Term: **14 Years**

(21) Appl. No.: **29/518,298**

(22) Filed: **Feb. 23, 2015**

(57) **CLAIM**

The ornamental design for a control handle for a medical device, as shown and described.

DESCRIPTION

FIG. 1 is a perspective view of an embodiment of a control handle for a medical device showing a new design;

FIG. 2 is a top view thereof;

FIG. 3 is a front view thereof;

FIG. 4 is a bottom view thereof;

FIG. 5 is a back view thereof;

FIG. 6 is a left side view thereof; and,

FIG. 7 is a right side view thereof.

The broken lines are for purposes of illustration only and form no part of the claimed design. FIGS. 1-7 are lined to represent the colors gray and green.

1 Claim, 7 Drawing Sheets
